[57] CLAIM

The ornamental design for a pivot-handled broom, as shown and described.

DESCRIPTION

FIG. 1 is a perspective;

FIG. 2 is a front view, the back view being identical thereto;

FIG. 3 is a top view;

FIG. 4 is a right-side view, the left-side view being identical thereto; and,

FIG. 5 is a bottom view.

The broken lines in FIG. 1 and FIG. 5 represent bristles and a handle, and form no part of the claimed design.
